UNITED STATES PATENT OFFICE.

ANTHONY RITSKY, OF NORTH BROOKFIELD, MASSACHUSETTS.

DIRECTION SIGNAL.

Application filed March 12, 1924. Serial No. 698,760.

To all whom it may concern:

Be it known that I, ANTHONY RITSKY, a citizen of the United States, residing at North Brookfield, in the county of Worcester and State of Massachusetts, have invented a new and useful Direction Signal, of which the following is a specification.

This invention relates to a direction signal for automobiles operated by internal combustion engines.

The principal objects of the invention are to provide for the operation of a direction signal by suction by connecting the same with the engine and regulating it with buttons within convenient reach of the operator in the car; also to provide a convenient mechanical arrangement by which the direction signal can be operated in the manner specified and one that is compact and neat and can be put on the mud guard and connected up with the engine without any serious alterations in the car.

Reference is to be had to the accompanying drawings, in which—

Fig. 1 is a front sectional view of a preferred embodiment of this invention applied to the mud guard of an automobile which is shown in transverse section;

Fig. 2 is a plan of the same with the cover removed;

Fig. 3 is an end view;

Fig. 4 is a sectional view of a part of the dash inside the car showing means for connecting and disconnecting the signal with the power and illustrating diagrammatically the connection with the engine; and

Fig. 5 is a sectional view on the line 5—5 of Fig. 4.

I have shown the invention as applied to one of the mud guards 10 of an automobile, although of course it can be applied to both of them if desired. The signal itself comprises a base 11 having three upstanding walls 12, 13 and 14. In practice these walls may be about an inch high or even less in some cases. The two walls 13 and 14 are parallel and spaced rather near together. Between them at their ends there is a solid square sectioned body of metal which extends in from the end of the device the necessary distance and is bored out to provide a cylindrical passage 15 open at the outer end and constituting a cylinder. This cylinder is closed by a cap 16 at one end and by a similar cap or internal wall 17 at the other. The latter is provided with a perfora-

ration and packing to surround the rod 19 of a piston. Resting on the walls 12, 13 and 14 is a cover 27 to complete the casing.

On the end of the piston rod is a rack 20. Between the walls 13 and 14 are two springs 21 pressing against the ends of the rack. One presses against the cap 17 and the other against a similar cap or wall 22 on the other end. These are for holding the rack normally in neutral position and resisting yieldingly its movement out of that position. On the side of the wall 14 there is cast a projection 23 which is bored out and provided with a spring 24 and ball 25 for engaging in a groove 26 in the rack and temporarily holding it in neutral position whenever it goes to that point.

Meshing with the rack is a gear 28 on the bottom of a hollow tube 29 that is adapted to seat down over a stationary stud 30 fixed on the base 11. This tube has at the top a hollow arrow 31 of any desired material and provided with a row of perforations 32 all around its edge. Within this arrow is supported an electric light 33 supplied by wires 34 from the battery and connected with the headlight switch of the car so that it will be turned on and off in accordance with the headlight.

For the purpose of connecting up the cylinder 15 with the source of power two tubes 35 and 36 are connected with the cylinder at opposite sides of the piston and pass to a suction box 37. Connected with each of these tubes there is a whistle 38 adapted to operate whenever a current of air passes through it. These two tubes are closed at their ends by valves 39 and a handle 40 resisted by springs 41. The suction is applied by connecting another tube 42 from the box 37 to the intake manifold of the engine. The engine in its operation creates enough vacuum so that whenever either one of the two buttons 40 is pulled the suction will act to move the piston 19 in one direction or the other and turn the arrow 31 in accordance therewith so that the arrow will indicate the direction which the car is to take.

Instead of the pull button construction shown, a push button arrangement can be used employing ordinary constructions well known.

An additional feature of the invention consists in the provision of a compartment 44 on the end of the signal arrow 31 with a

lamp inside connected up with the battery down through the column 29. This compartment is separated from the interior of the arrow by an opaque wall or walls and the lamps are lighted either at the same time or separately as desired. This lamp in the compartment 44 will illuminate that separately. On the rear end of this compartment is a transparent or translucent plate having some sign or word to indicate that the vehicle is to slow up or stop and I have shown the word Slow for that purpose. On top of this I provide a mirror 45 which obviously, when the arrow is pointing ahead, will enable the driver to see what is behind him, this mirror being located transversely on the rear end of the arrow.

The lamp in the compartment 44 is connected with an electric push button 46 adjacent to the buttons 40 for connecting up the line to the lamp that illuminates the "slow" signal.

I also find it an advantage to provide an additional button 47 and connect it with the suction box 37 for operating the horn from the suction. The method of its operation need not be described in detail as it is the same as that above described.

Of course it will be understood that the "slow" signal can be operated by the horn button, if desired, without an extra button, or by the brake lever or the button can be put on under the operator's foot so that when he wants to make the signal he will step on the button and the light will go on to show the signal slow. As soon as he takes his foot off the signal will be dark. It will be understood that the ordinary electric horn can be removed and the suction horn used in place of it, as stated above. This makes it a three in one complete device consisting of a signal indicator, "slow" signal and suction horn.

Even if all these features are not used, the direction signal itself is an important invention. If the driver is going along the road in the usual way and he wishes to turn to the left for any purpose whatever, he turns the arrow to the position shown in Fig. 1. Then when he has turned around on the road on the left he allows it to come back to neutral so that the arrow assumes the position illustrated in Fig. 3. In this position the operator can look at the mirror 45 and see what is behind him and also when he wishes to slow up he can show the "slow" signal and turn the arrow afterwards if he wishes to go to the right or left.

In other words, if there is a car following him and he wishes to turn either right or left he operates the button 46 to light up the lamp in the compartment 44. This shows the party behind him that he is going to slow up and indicates to that party that he expects to turn in one direction or the other.

He then operates the proper button 40 to turn the arrow and show which way he is to turn. The party behind him will observe the signal and there will be no danger of an accident.

On the other hand if he is trying to pass another party he will show that up clearly to the driver behind him and also if the party behind him wishes to pass he will know where he is going.

This constitutes a very simple device to install, one having very few parts that are likely to wear and get out of order. It requires no additional power and no other drain on the battery except for the light. It is safe and sure to operate whenever the engine is running. It cannot be operated when the engine is standing still. Even when the motor is idling sufficient power is generated to operate this device to show how the driver is going to start his car. The apparatus can be installed very readily without making any important changes in the car and in fact, without even drilling many holes. It requires no expense in its operation as the power is taken from the engine and this is power that is entirely wasted under ordinary circumstances.

It will be understood that although I prefer to operate the various features in the manner set forth, I am aware that electric coils, compressed air or any other motive power can be used to operate the signal.

Although I have illustrated and described only a single form of the invention I am aware of the fact that modifications can be made therein by any person skilled in the art without departing from the scope of the invention as expressed in the claims. Therefore I do not wish to be limited to all the details of construction herein shown and described but what I do claim is:—

1. In a direction signal, the combination of a cylinder and a piston therein, a pair of tubes connected with the cylinder at opposite sides of the piston, a suction box into which said tubes extend, and individual valves for opening and closing said tubes in the suction box, with the intake manifold of an internal combustion engine connected to the suction box, a direction signal, means connected with the piston for turning said signal, and means for giving an audible signal whenever air passes through either of said pair of tubes.

2. In a direction signal, the combination of a supporting base having a pair of walls, a cylinder, a piston in said cylinder having a piston rod extending from it, a rack on said piston rod, a pair of springs bearing on opposite ends of said rack for resisting motion of the piston from neutral position, a gear meshing with said rack and having a shaft extending upwardly therefrom, a stud on said base extending into the shaft

- for centering and holding it in position, and a signal device on top of said shaft and a cover over said base resting on said walls and having a perforation for said shaft.
5. 3. In a direction signal, the combination of a supporting base having a pair of integral walls spaced apart, a cylinder located between said walls, a piston in said cylinder having a piston rod extending from it, a rack 10 on the end of said piston rod, a pair of springs bearing on opposite ends of said rack and located between said walls for resisting motion of the piston from neutral position, a gear meshing with said rack and having a hollow shaft extending upwardly therefrom, a hollow stud on said base extending into the hollow shaft for centering and holding it in position, and a signal device on top of said hollow shaft provided 15 with an electric light therein, the wires of which extend down through the hollow shaft and stud, whereby the electric signal will be turned when the piston is moved, and a cover over said base resting on said walls 20 and having a perforation for said hollow shaft.
4. The combination with a cylinder, a piston therein, a pair of tubes connected with the cylinder at opposite sides of the piston, a suction box into which said tubes extend, a third tube connected with the suction box for operating a horn, and individual valves for opening and closing said tubes with the intake manifold of an internal combustion 25 engine connected to the suction box, a direction signal, means connected with the piston for turning said signal.
5. The combination with a cylinder, a piston therein, and means connected with the 30 intake manifold of an internal combustion
- engine for moving said piston in either direction by suction created by the engine, of a direction signal mounted to turn, means connected with said piston for turning said signal, and means connected with the manifold for sounding a horn. 45
6. The combination with an internal combustion engine having an intake manifold, of a direction signal, and a slow signal, of means connected with the manifold for mechanically operating said direction signal and a horn at will, and electric means for displaying the slow signal. 50
7. The combination with a tube, a suction box, tubes extending into it, and individual valves for opening and closing said tubes, of the intake manifold of an internal combustion engine connected to the suction box, and means connected with a horn for operating it when the proper valve is opened. 55
8. In a direction signal, the combination of a signal device mounted to turn so as to point either to the left or right or ahead, means for illuminating it, said device having a separate compartment on the rear and provided with a slow signal, and an independent electric lamp for illuminating the slow signal. 60
9. In a direction signal, the combination of a signal device mounted to turn so as to point either to the left or right or ahead, said device having a compartment on the rear provided with a slow signal, an electric lamp for illuminating the slow signal, and a transverse mirror on the rear of the signal. 70
- 75

In testimony whereof I have hereunto affixed my signature.
